READY COMPUTER

Henry Watson, Calgary, Alberta, Canada

Application November 10, 1937, Serial No. 173,915
In Canada December 1, 1936

4 Claims. (Cl. 235—86)

This invention relates to improvements in a ready computer and appertains particularly to an instrument of this kind designed for the building trade for use in roofing.

5 An object of the invention is to provide a ready computer that will provide instantly all the essential figures for framing either a hip or octagonal roof without knowledge of calculating with a steel square.

10 A further object of the invention is to provide a ready computer of this kind for roofers in which a pair of endless belts, bearing the necessary indicia, are mounted parallel within a portable casing, and are each partly visible through 15 its own window in opposite sides of the casing.

A further object of the invention is to provide a handy instrument of this kind capable of being adapted to many uses of which that described is but an apparent and at present seems a desirable 20 one.

A further object of the invention is to provide an operating mechanism for an instrument as aforesaid or the like for propelling a ribbon or endless belt without danger of slipping and without supporting the ribbon or belt in any way.

25 A still further object of the invention is the provision of an instrument and operating mechanism therefor of the nature and for the purposes described that is characterized by structural simplicity, efficiency and durability, and being capable of production at low cost is thereby rendered commercially desirable.

To the accomplishment of these and related 30 objects as shall become apparent as the description proceeds, my invention resides in the construction, combination and arrangement of parts as shall be hereinafter more fully described, illustrated in the accompanying drawing and pointed out in the claims hereunto appended.

40 The invention will be best understood and can be more clearly described when reference is had to the drawing forming a part of this disclosure wherein like characters indicate like parts throughout the several views.

45 In the drawing:

Figure 1 is a plan view of the instrument;

Figure 2 is a longitudinal vertical section, as taken on line 2—2 of Figure 1 in the direction indicated by the arrows; and

50 Figure 3 is a transverse vertical section thereof as taken along the line 3—3 of Figure 2 looking in the direction indicated by the arrows.

The device is shown in the form of a handy pocket instrument comprising a rectangular cas-

ing 5 having corresponding sides 6, ends 7 and a top 8 and bottom 9. These are assembled and secured in position in any suitable manner as by the small fastening screws 10 illustrated.

5 A pair of parallel rollers 11 are positioned near each end of the casing 5 on transverse spindles or bushings 12 whose opposite ends are journaled in the side walls 6 and encircling corresponding pairs of idler rollers 11 respectively, near opposite ends of the casing 5 are two endless steel ribbon belts 13. The belts are provided near each edge with a continuous row of oblong perforations 14 and carry on their outer surfaces a continuous series of transverse panels of indicia 15, one of which is readable at a time through a correspondingly sized window 16, for the upper belt 13, in the casing top 8; and one of the panels on the lower belt through a similar window 17 in the bottom 9.

The indicia on the panels is arranged in vertical rows for horizontal registry with identifying descriptions 18 on the top 8 and bottom 9 alongside the respective windows 16 and 17 and provides at a glance all the ready-calculated cuts for rafters, purlins, and sheeting, on the top belt 10 for hip roofs and on the lower belt for octagonal roofs, for any pitch from 1 inch to 24 inches rise per foot run.

20 Between the parallel pair of rollers 11 near one end of the casing is a rotatable shaft 19 journaled at one end in one of the sides 6 but at its other end projecting right through the opposite side of the casing and carrying a knurled wheel 20 on its exposed end. A pair of spaced sprocket wheels 21 are rigidly attached to the shaft 19 within the casing, one near each side for engagement with the rows of perforations 14 in the belts 13 into and through which the sprocket wheel teeth extend. For the reception of the sprocket wheel teeth after passing through the perforations in the ribbon belts annular grooves 22 are provided near opposite ends of each of the pair of rollers 11 engaged by these sprocket wheels 21. The result is a belt operating mechanism that is positive and cannot slip under any circumstances 30 even if it was heavily loaded. The sprockets cannot spread away from either or both the adjacent rollers, the idler rollers carry all the fixed load of the belts and the belts are supported throughout their width by the rollers at the time of engagement by the sprockets excepting only for the narrow cutaway sprocket accommodating grooves so the sprocket teeth must extend completely through the perforations and into these grooves and nothing short of the tearing of the 35

belts or the stripping of the sprocket teeth can defeat the positive rotation of the belts on the actuation of their propelling sprocket.

From the foregoing description taken in connection with the accompanying drawing, it will be manifest that a ready computer and operating mechanism therefor is provided that will fulfill all the necessary requirements of such a device but as many changes could be made in the above description and many apparently widely different embodiments of my invention may be constructed within the scope of the appended claims without departing from the spirit or scope thereof, it is intended that all matters contained in the said accompanying specification and drawing, shall be interpreted as illustrative and not in a limitative or restrictive sense.

Having thus described the invention, what I claim as new and desire to secure by Letters Patent is:

1. A computer comprising a casing, a pair of windows in opposite sides thereof, a pair of parallel belts rotatably mounted in said casing respectively visible through said opposite windows and a common belt engaging means for revolving both of said belts in unison.

2. An instrument for rapid computing and the like comprising a casing having a transversely disposed window therein; a free idling roller in each end thereof, an endless belt running around said rollers so that a portion thereof is always

in registry with and visible through said window, a row of perforations near each edge of said belt and operating mechanism engaging in the perforations of said belt at some point in the arc of contact of said belt with one of said supporting 5 idler rollers.

3. An instrument or the like comprising a casing, a transversely disposed window therein, a transverse roller freely journalled near each end of said casing, an endless belt running around 10 said rollers, a portion of which is always in registry with and visible through said window, a row of perforations near each edge of said belt, an annular groove cut near each end of one of said rollers spaced equal with the distance between 15 opposite rows of perforations in said belt, and belt moving sprockets engaging said belt at some point in the arc of contact of said belt with the grooved roller whose teeth are adapted to pass through the perforations in said belt and into 20 said grooves.

4. An instrument for rapid computing and the like comprising in combination with the structure set forth in claim 1, free rollers in opposite ends of said casing for carrying said pair of parallel 25 belts, a continuous series of transverse panels of indicia in vertical rows on said belts readable one panel on each belt at a time through said windows, and identifying descriptions on said casing alongside said windows in horizontal registry 30 with the vertical rows of indicia in said panels.

HENRY WATSON.
